UNITED STATES PATENT OFFICE.

WILLIS H. SMITH, OF KNOXVILLE, TENNESSEE.

STEAM-ENGINE VALVE-GEAR.

1,086,476.

Specification of Letters Patent.

Patented Feb. 10, 1914.

Application filed November 15, 1913. Serial No. 801,199.

To all whom it may concern:

Be it known that I, WILLIS H. SMITH, a citizen of the United States, residing at Knoxville, in the county of Knox and State 5 of Tennessee, have invented certain new and useful Improvements in Steam-Engine Valve-Gears, of which the following is a specification.

This invention relates to improvements in 10 the steam-engine valve-gear disclosed in the U. S. Patent No. 1,033,532, dated July 23, 1912, and the object of the present invention is to simplify said gear and to reduce the 15 number of parts, thus cheapening the structure to a considerable extent.

The patent referred to discloses a slide block and a guide therefor, which parts have been eliminated in the present construction.

20 In order that the invention may be better understood, reference is had to the accompanying drawing, in which—

Figure 1 is a side elevation of the gear, and Fig. 2 is a plan view thereof.

25 Referring specifically to the drawing, 5 denotes a drive wheel having a main crank 6 to which the pitman 7 is connected. To the crank 6 is connected an auxiliary crank 8. It may be here stated, that the gear is 30 designed primarily for locomotives, although it is not limited thereto. For engines other than locomotive engines, the crank 6 will be on a crank disk fast on the drive shaft. To the crank 8 is connected 35 one end of a pitman 9, the other end of which latter is connected by a link 10 to a rocker arm 11 fast on a transverse shaft 12. The shaft 12 also has a rocker arm 13 set 40 at substantially a right angle to the arm 11. The valve rod 14 is connected to the arm 13. The arms 11 and 13 constitute a bell- 45 crank lever which transmits motion to the valve rod from the link 10 and the pitman 9. The shaft 12 is mounted in suitable bearings 15 carried by the frame of the locomotive, and the parts mounted on said shaft, as well as the associate parts hereinbefore

described are, of course, duplicated on the opposite side of the locomotive, except when the gear is applied to a stationary or other 50 engine having only one cylinder.

The foregoing parts are all arranged and they operate in the same manner as in the Patent Number 1,033,532 hereinbefore referred to.

55 In bearings 16 on a suitable support 17 carried by the frame of the locomotive is mounted a transverse shaft 18 having two rocker arms 19 and 20, respectively arranged at an angle to each other. To the support 60 is also pivoted, as indicated at 21, an arm 22. The arms 20 and 22 are parallel and connected by a link 23, so that they may swing together.

To the pitman 9, intermediate the ends 65 thereof, as indicated at 30, is pivotally connected one end of a link 31, the other end of which latter is pivotally connected to the link 23, as indicated at 32. The link 31 corresponds to the link which is shown in 70 the Patent Number 1,033,532 connected to a slide block. This slide block and the guide therefor are eliminated in the present construction, the parts 20, 22 and 23 being substituted therefor. The arm 19 is connected 75 by a rod 33 to a reversing lever 34 provided with the usual locking means. The parts 20, 22 and 23 are also duplicated on the other side of the locomotive.

When the lever 34 is operated, the arms 80 20 and 22 swing in parallelism, which shifts the link 23, producing the same effect on the link 31 as the slide block in the patent hereinbefore referred to.

The number of parts which make up the 85 gear is reduced to a minimum and the structure is greatly simplified and cheapened, and it can be readily installed.

I claim—

1. A steam-engine valve-gear comprising 90 a pair of parallel swinging arms, a link connecting said arms, means for swinging the arms, an auxiliary crank, a rod connected to said crank, a link connection between the

rod and the aforesaid link, and a second link connected to the rod and having an operative connection with the engine valve.

2. A steam-engine valve-gear comprising
5 a rock shaft, an arm on said shaft, a pivoted
arm, a link connecting said arms, means for
operating the rock shaft, an auxiliary crank,
a rod connected to said crank, a link con-
nection between the rod and the aforesaid

link, and a second link connected to the 10
rod and having an operative connection with
the engine valve.

In testimony whereof I affix my signature
in presence of two witnesses.

WILLIS H. SMITH.
